13549

JAN 30, 1883

UNITED STATES PATENT OFFICE.

ALFRED A. POPE, OF CLEVELAND, OHIO.

DESIGN FOR A HARNESS-BIT.

SPECIFICATION forming part of Design No. 13,549, dated January 30, 1883.

Application filed November 11, 1882. Term of patent 14 years.

To all whom it may concern:

Be it known that I, ALFRED A. POPE, of Cleveland, in the county of Cuyahoga and State of Ohio, have invented and produced a new and original Design for Harness-Bits, of which the following is a specification, reference being had to the accompanying photograph, making a part thereof.

My invention relates to a novel design for harness-bits; and it consists in certain features of configuration and ornamentation, all of which will be described hereinafter in this specification, and will be particularly pointed out in the claims thereof.

15 Two views accompany this specification, that at Figure 1 representing what is known as a "half-cheek" snaffle-bit, and that at Fig. 2 representing a "full-cheek" snaffle-bit.

In both photographic illustrations the same 20 part will be found designated by the same reference-letter.

A is the mouth-piece or bit proper, B B the rein-rings, and C C the cheek-pieces. The ring B and cheek-piece C are cast integral, 25 and as a whole form a new design. The ring is made thicker where it joins the bit and where the neck of the cheek-piece touches the ring. From this neck the cheek-piece is made like an open frame, whose sides gradually 30 spread outward, and are connected at their

outer extremities by an end bar curved in form. The sides of this frame-like portion are connected by three parallel bars set at inclinations, which bars serve to make the cheek-piece still more ornamental or handsome in 35 appearance.

Of course my novel design may be employed in either a half-cheek bit, as seen at Fig. 1, or in a whole-cheek bit, as seen at Fig. 2, and in any other kind of bit than that of a snaffle-bit, my invention resting particularly in the 40 design of the rings and cheeks proper.

What I therefore claim as new, and desire to secure by Design Letters Patent, is—

1. In a harness-bit, the ring B and cheek-piece C, made substantially as shown and described. 45

2. In a harness-bit, the cheek-piece C, tapering in form with straight sides and rounded end. 50

3. In a harness-bit, the cheek-piece C, made frame-like and with inclined bars connecting the sides of the frame.

In witness whereof I have set my hand this 3d day of November, 1882.

ALFRED A. POPE.

In presence of—

WALTER A. BIDDLE,
GEORGE F. EBERHARD.
